US0D1003652S

(12) **United States Design Patent** (10) **Patent No.:** **US D1,003,652 S**
(45) **Date of Patent:** **** Nov. 7, 2023**

(54) **COOKWARE**

(71) Applicant: **Lagom Kitchen Co.**, Culver City, CA (US)

(72) Inventors: **Amir Tehrani**, Los Angeles, CA (US); **Zachary Rosner**, Los Angeles, CA (US)

(73) Assignee: **Lagom Kitchen Co.**, Culver City, CA (US)

(**) Term: **15 Years**

(21) Appl. No.: **29/831,831**

(22) Filed: **Mar. 23, 2022**

(51) LOC (14) Cl. **07-02**

(52) U.S. Cl.

USPC **D7/360**; D7/354; D7/361

(58) **Field of Classification Search**

CLAIM

The ornamental design for a cookware, as shown and described.

DESCRIPTION

FIG. 1 is a perspective view of a cookware showing our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dotted lines represent portions of the cookware that form no part of the claimed design.

1 Claim, 6 Drawing Sheets
